[57] CLAIM

The ornamental design for a calculator housing or similar article, as shown and described.

DESCRIPTION

FIG. 1 is a top plan view of a calculator housing or similar article showing my new design, the broken line showings of buttons and strap being environmental only and forming no part of the claimed design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a right, front and top perspective view thereof.

FIG. 1

FIG. 2

FIG. 3

FIG. 4

FIG. 5
